UNITED STATES PATENT OFFICE.

WILLIAM PRESTON HARTFORD AND CLARENCE MONROE RICKOFF, OF CHICAGO,
ILLINOIS; SAID RICKOFF ASSIGNOR TO SAID HARTFORD.

ELECTRIC LANTERN.

1,168,724.

Specification of Letters Patent. Patented Jan. 18, 1916.

Application filed August 7, 1915. Serial No. 44,301.

To all whom it may concern:

Be it known that we, WILLIAM PRESTON HARTFORD and CLARENCE MONROE RICKOFF, citizens of the United States, residing at 5 160 North Fifth avenue, Chicago, in the county of Cook and State of Illinois, have invented certain new and useful Improvements in Electric Lanterns, of which the following is a specification.

10 This invention relates to new and useful improvements in portable electric lanterns, and the primary object of the invention is to provide in a device of this character, a simple and efficient circuit controlling means, 15 as well as a neat and compact device for securing in the lantern its source of electric energy.

A further object of this invention is to provide a device of this character which 20 will be easy and simple to manufacture, very efficient in operation, and one that will be very inexpensive to produce.

With these and numerous other objects in view, our invention consists of the certain 25 novel details of construction, combination, and arrangement of parts which will be hereby referred to and more particularly pointed out in the specification and claims.

In the drawings:—Figure 1 is a side elevation of the lantern. Fig. 2 is a vertical section on the line 2—2 of Fig. 1. Fig. 3 is a vertical section taken at right angles to the section of Fig. 2. Fig. 4 is a bottom view of the lantern with the bottom plate and 35 battery removed. Fig. 5 is the same as Fig. 4 only showing battery attached.

In describing our invention, we shall refer to the drawings in which similar reference characters designate corresponding parts 40 throughout the several views, and in which the numeral 1 designates the base portion of our improved electric lamp. This base portion 1 has projecting upwardly from the top thereof an annular flange or collar 2 which 45 is internally threaded to receive the lower portion of a transparent globe 3. This globe 3 which is formed preferably of glass has its upper portion threaded, to securely hold thereon a threaded cap or cover 4, which has 50 a plurality of perforations 5, therein to allow air to circulate in the globe when placed thereon.

A bail 6 is attached to the cap or cover 4 through apertures at diametrically opposite 55 points thereon, and is adapted to form a

handle such as is used on lanterns of this general type.

The base 1 of this lantern comprises a receptacle in two detachable parts, which are designated, the upper section by the numeral 7, and the lower section by the numeral 8. The section 8 is adapted to frictionally engage the section 7, for a short distance limited by the rib 9 formed thereon, and to be held in engagement therewith. 60 The bottom section 8 will be readily detachable from the upper section 7, at any time it may be desired to remove the same for a purpose to be hereinafter more fully set forth.

70 Positioned in the upper section 7 of the base 1 is a substantially U-shaped spring clamp 10, which has a recessed portion intermediate its ends having therein a central aperture 11 and an aperture 12 disposed to one side of the same. The aperture 12 is adapted to receive a fastening member 13 which securely holds the recessed portion in engagement with the lower surface of the section 7 of the base 1. This clamp 10 80 is composed of a strip of spring metal and its arms are bent S-shaped with their extremities outward so that upon the insertion of an article therebetween, there will be no danger of cutting the fingers upon the 85 sharp edges of the same. A battery B, of the flat dry cell variety, is adapted to be held transversely between the said arms of the clamp, and the terminals 16 and 17 of the same are disposed at one end of the 90 same.

Extending transversely across the upper portion of the base, and disposed at right angles to the clamp 10, is a metallic strip 18, having a downturned end 19, for engagement with the terminal 17 of the battery, and a recessed portion adjacent the other end with a central aperture 20 therein aligning with the aperture 11 in the clamp 10. The strip 18 has a V-shaped foot 21 adjacent its end 19 which helps hold the same from proximity with the lower surface of the section 7 and also presents a larger flat surface upon which the battery B rests. A strip of insulating material 22 is interposed between the metallic strip and the clamp and base sections.

100 Positioned centrally on the upper section of the base, in the flange 2 is an incandescent electric lamp socket 23, having secured 110

therein a lamp 24. This socket 23 is surrounded by a centrally apertured convexed reflector plate 25, which will accentuate the brilliancy of the light emanating from the 5 lamp 24.

Projecting downwardly through the socket 23 is a headed screw 26, which projects through the top of the base, and through the alining apertures 11 and 20, 10 in the clamp and strip respectively, being secured to the strip by a locking nut 27 on its lower end. This screw is held from contact with the base and clamp by insulating washers 28 thereon.

15 An apertured washer 29 is positioned in the bottom of the socket 23 through which the screw projects, and the lamp 24 when positioned in said socket, contacts with the head on said screw.

20 The upper section 7 of the base 1 has positioned therethrough, at a point adjacent the terminal 16 of the battery B, an internally threaded bore 30, in which is mounted a contact screw 31, having thereon a head 25 32, which is positioned on the outside of the casing. This screw 31 is adapted to move in or out of contact with the terminal 16, upon rotation, to control the circuit through the battery of this lamp.

30 The operation of this lamp is as follows: When it is desired to light the same, the screw 31 is rotated until the same contacts with the terminal 16 of the battery, whereby the lamp will be ignited owing to the fact 35 that the other terminal 17 of the battery is connected to the lamp through the strip 18, and the screw 26. This rotatable screw 31 affords a simple and efficient means for lighting and extinguishing the lantern.

40 Owing to the base of this lantern being made in two sections, upon the dry cell battery becoming exhausted, the bottom section of the base may be removed and the battery taken out and replaced by a fresh 45 one. The applicability of this lantern to the use of dry cell batteries of the flat variety, makes this a small and compact portable self-contained lighting source, electric lantern, the utility and novelty of which are 50 apparent.

From the foregoing description of our improved electric lantern, the manner of applying the same to use, and the operation thereof will be readily understood, and it 55 will be seen that we have provided a simple and durable device that will be easy to manufacture and very efficient in operation.

What is claimed as new is:—

1. An electric lantern comprising a base 60 including a receptacle having a detachable bottom portion, a battery disposed transversely in said receptacle, a substantially

U-shaped spring clamp secured to the upper 65 portion of said receptacle and adapted to hold the battery between its arms, an incandescent lamp positioned above said receptacle, a metallic strip connected to one terminal of the battery extending across the 70 upper portion of the receptacle and insulated therefrom, a screw extending through the top of said receptacle connecting the lamp and metallic strip, and a movable contact point carried by the receptacle for engagement with the other terminal of the battery. 75

2. An electric lantern comprising a base, including a receptacle having a detachable bottom portion, a battery disposed transversely 80 in said receptacle, a substantially U-shaped spring clamp secured to the upper portion of said receptacle and adapted to hold the battery between its arms, an incandescent lamp positioned above said receptacle, a 85 metallic strip connected to one terminal of the battery extending across the upper portion of the receptacle and insulated therefrom, a screw extending through the top of said receptacle connecting the lamp and metallic strip, said upper portion of the receptacle having an aperture through the side thereof adjacent the other terminal of the battery, and a contact screw positioned through the same and movable in and out 90 of engagement with the said terminal. 95

3. An electric lantern comprising a base including a receptacle having a detachable bottom, a battery disposed transversely in said receptacle, a substantially U-shaped 100 clamp having S-shaped spring arms to hold said battery secured to the said receptacle, a socket and incandescent lamp positioned above said receptacle, a curved apertured reflector plate surrounding said socket and resting on the upper surface of the receptacle, a screw extending downwardly from the lamp socket through the top of the receptacle, a metallic strip positioned at right angles to the clamp connected at one end to 105 one terminal of the battery, and at the other to the screw, said strip being bent to form a flat battery receiving surface, an insulating strip between the metallic strip and the receptacle and clamp, and a contact screw 110 carried by the receptacle and movable in and out of engagement with the other terminal of the battery. 115

In testimony whereof we affix our signatures in the presence of two witnesses.
